PAIR OF NOVELTY SUNGLASSES

Marvin I. Glass and Henry Stan, Chicago, Ill., assignors to Marvin Glass & Associates, Chicago, Ill., a partnership

Filed May 20, 1965, Ser. No. 85,372

Term of patent 14 years

(Cl. D57—1)

The dominant features of our design reside in the portions shown in full lines.

The temple portions have been omitted in FIGURES 2-6 for convenience of illustration.

We claim:

The ornamental design for a pair of novelty sunglasses, substantially as shown and described.
